UNITED STATES PATENT OFFICE.

STEPHAN CSUTHY, OF CLEVELAND, OHIO.

INVALID-BED.

No. 920,922.

Specification of Letters Patent.

Patented May 11, 1909.

Application filed December 23, 1908. Serial No. 468,901.

To all whom it may concern:

Be it known that I, STEPHAN CSUTHY, a subject of the Emperor of Austria, residing at Cleveland, in the county of Cuyahoga and State of Ohio, have invented certain new and useful Improvements in Invalid-Beds; and I hereby declare the following to be a full, clear, and exact description of the invention, such as will enable others skilled in the art to which it pertains to make and use the same.

This invention relates to new and useful improvements in invalid beds.

The object of this invention is to provide a bed having such an arrangement of parts that the patient or person occupying the same may be lifted vertically or shifted horizontally by a corresponding moving or shifting of a portion of the bed, thereby doing away with the necessity of having to handle the patient which is hard on the attendants or nurses and frequently occasions suffering to the patient.

By the use of my invention it is possible to lift the patient above the bed by means of a frame on which the patient lies and then to shift the frame sidewise on to an operating table, if necessary, without having to place the hands at all on the patient. The patient can also be lifted in the same way when it is desired to change the linen on the bed or when it is necessary to insert bandages or dressings beneath or around the patient.

With these objects in view my invention consists in the features of construction and combination of parts as described in the specification, pointed out in the claims and illustrated in the accompanying drawings.

In the accompanying drawings Figure 1 is a side elevation of a bed embodying my invention. Fig. 2 is a section on line 2—2, Fig. 1. Fig. 3 is a section on line 3—3, Fig. 2. Fig. 4 is a section on line 4—4, Fig. 1. Fig. 5 is a section on line 5—5, Fig. 4.

As shown in the drawings the main frame of the bed comprises a head-piece consisting of two upright posts, 1 and 1' and a cross-piece 1², a foot-piece also consisting of two upright posts 2 and 2' and a cross-piece 2² and side members 3 and 4, all the members being preferably formed of channel iron. On the side-pieces 3 and 4 are formed longitudinally extending shoulders 3' and 4' which constitute the supports for the ends of the

laths 5 on which is arranged a mattress 10. 55 In the posts 1 and 1' of the head-piece are formed vertical guideways 6 and 6', and likewise in the posts 2 and 2' of the foot-piece are formed vertical guideways 8 and 8' respectively, and in said vertical guideways 6 and 6' and 8 and 8' are slidably arranged rack-bars 7 and 7' and 9 and 9', respectively. In the head and foot pieces are mounted horizontal shafts 11 and 12 and on the shaft 11 are secured gear wheels 13 and 13' which are adapted to mesh with the teeth on the rack-bars 7 and 7', respectively. On the shaft 11 are also mounted two sprocket wheels 14 and 14' and two beveled gears 15 and 15', the object of which will appear later. On the outer 70 end of the shaft 11 is secured a crank-arm 16 and a ratchet wheel 17, and in proximity to the ratchet wheel on the side of the post 1 is mounted a pawl 18 which is adapted to engage with and lock the ratchet wheel against 75 movement in one direction. On the shaft 12 are rigidly secured two gear wheels 19 and 19' which are arranged to engage with the teeth on the rack-bars 9 and 9', and also two sprocket wheels 20 and 20' and two beveled 80 gears 21 and 21', the object of which will appear later. In order to transmit motion from the shaft 11 to the shaft 12 two shafts 22 and 22' are arranged in the channels in the side pieces 3 and 4, respectively, and on the 85 shaft 22 are secured beveled gears 23 and 23' which mesh with the beveled gear 15 on the shaft 11 and the bevel gear 19 on the shaft 12, and on the shaft 22' are secured beveled 90 gears 24 and 24' which mesh with the beveled gear 15 on the shaft 11 and 19' on the shaft 12. It will therefore be seen that when the shaft 11 is driven by means of the crank arm 16 the motion will be transmitted to the shaft 12 and the rack-bars 7 and 7' and 9 and 9' 95 will all be raised together.

25 represents a rectangular frame having a length and width slightly greater than the length and width of the mattress. To the corners of this frame 25 are secured arms 26 and 26' and 27 and 27' which are secured in any suitable manner to the upper ends of the rack-bars 7 and 7' and 9 and 9', respectively, and therefore when the said rack-bars are raised the frame 25 will be lifted up thereby, 100 On the top of the frame 25 is arranged a frame 28 of similar dimensions. On the end bars of the frame 28 are mounted rollers 29

so as to travel on the end bars of the frame 25 permitting the frame 28 to be readily shifted transversely of the said frame 25. In the end bars of the frame 28 are also formed 5 small openings 30, the object of which will be explained hereinafter. A series of straps 31 extend from side to side of the frame 28 and are preferably formed of leather and arranged to lie on top of the mattress 10. At 10 the end of the frame 28, near the head of the bed is hinged a small frame 32 for supporting the head and shoulders of the persons occupying the bed. The frame 32 is provided with projections 33 and 33'. A shaft 34 extends between the posts 1 and 1' and on said shaft are rigidly secured arms 35 and 35' which are arranged to engage with the projections 33 and 33'. One end of the shaft 34 is provided with a crank arm 36 and a 15 ratchet wheel 37 and on the side of the post 1 is mounted a pawl 38 which is arranged to engage with the ratchet wheel 37. It will be seen that by turning the crank arm 36 the arms 35 and 35' will be swung up tilting up the 20 frame 32 and forming a support therefor at the desired angle, and the engagement of the pawl with the ratchet wheel will hold the arms in the proper position. Near the top of the head and foot pieces of the bed frame 25 are arranged small shafts 40 and 41 on which are sprocket wheels 42 and 43 respectively. The sprocket wheels 42 are operatively connected with the sprocket wheels 14 and 14' 25 on the shaft 11 by sprocket chains 44 and the sprockets 43 are operatively connected with the sprocket wheels 20 and 20' on the shaft 12 by sprocket chains 45. It will therefore be understood that when the crank arm 16 is operated the shafts 40 and 41 will be 30 driven through their operative connection with the shafts 11 and 12. On the shafts 40 and 41 are formed screw-threads 47 and 48 respectively, and on the screw-threaded portions of said shafts 40 and 41 are arranged 35 pairs of screw-threaded blocks 49 and 50, respectively, the pairs of blocks being preferably connected by bars 51 and 52, respectively. On the pair of blocks 49 are rotatably mounted small sheaves 53 and on the 40 pair of blocks 50 are mounted small sheaves 54. Ropes 55 are arranged on the sheaves 53 and each rope is provided at one end with a hook 56 and at its other end with a counter-balancing weight 57 and likewise ropes 59 are arranged on the sheaves 54 and are 45 provided with hooks 60 and counter-balancing weights 61. It will therefore be seen that when the shafts 40 and 41 are rotated the sheaves on said shafts will be caused to 50 travel lengthwise on said shafts carrying along with them the ropes which are mounted thereon.

The mattress 10 is preferably leather covered and may be provided with a drainage 55 channel 10'.

The operation of the parts heretofore described are as follows. When the bed is occupied the person therein will lie on top the frame 28. If it is desired to raise the occupant so as to change the linen on the bed or in order to get unrestricted access to the body of the patient as is necessary when bathing the patient or applying bandages the crank arm 16 will be operated thereby raising the rack-bars which will carry up the frame 25 together with the frame 28 which rests thereon and the patient will be lifted clear of the mattress. If it is desired to remove the patient entirely from the bed the hooks on the ends of the ropes are caused to engage with 70 the openings 30 in the end bars of the frame 28 and the crank arm 16 is then operated, which will as before stated, raise the rack bars thereby lifting up the frames 25 and 28, but as the frame 28 has been coupled to the 75 ropes as the two frames move up together the frame 28 will be caused to travel transversely of the frame 25 so that the frame 28 will both move vertically and horizontally at the same time so that when it has been raised the required distance the said frame 28 will project beyond the side of the bed a sufficient distance to permit it to be readily taken hold of by attendants and either carried away or 80 shifted upon an operating table which may be shoved under the frame before it is entirely removed from the bed.

What I claim is,—

1. In an invalid bed, the combination with 100 a main frame, of means for supporting a mattress thereon, vertical guideways formed in said main frame, rack-bars slidably mounted in said guideways, a frame arranged above said mattress and operatively secured to said 105 rack-bars, gear wheels mounted in the main frame and arranged to mesh with the said rack-bars, means for simultaneously actuating said gear wheels, a frame provided with means for independently supporting the patient arranged on top of said last-mentioned 110 frame and means for shifting said uppermost frame transversely of the frame on which it rests simultaneously with the upward movement thereof.

2. In an invalid bed the combination with 115 a main frame, of means for supporting a mattress thereon, vertical guideways formed in said main frame, rack bars slidably mounted in said guideways, gear wheels mounted in said main frame and arranged to mesh with said rack-bars, means for simultaneously actuating said gear wheel, a frame arranged above said mattress and operatively secured to said 120 rack-bars, a frame provided with means for independently supporting the patient slidably mounted on said rack-bar supported frame, shafts mounted in the head and foot pieces of the main frame and provided with exterior screw-threads, blocks arranged on said shafts and provided with cor- 125 130

responding interior screw-threads, sheaves mounted on said blocks and ropes provided with weights at one end and at their other end with means for engaging the uppermost frame, substantially as described and for the purpose set forth.

5 In testimony whereof, I sign the foregoing

specification, in the presence of two witnesses.

STEPHAN CSUTHY.
